UNITED STATES PATENT OFFICE.

MORTIMER P. LAWTON, OF ATLANTA, GEORGIA, ASSIGNOR TO ATLANTIC STEEL COMPANY, OF ATLANTA, GEORGIA.

BAND-BENDING AND BUCKLE-ATTACHING MACHINE.

Application filed June 15, 1926. Serial No. 116,190.

This invention relates to a machine for bending metallic straps or bands and attaching buckles to an end of each band.

More particularly, it relates to a machine for making straps or bands suitable for banding bundles of cotton ties, hoops, steel bars, or similar materials, although, of course, it could be used for a variety of purposes.

An object of the invention is to provide bands suitable for use in a method of banding bundles wherein the completed bands will be tightly arranged upon the bundles and the joined part of the band will lie flat against the bundle.

Another object is to provide bands suitable for use in a method of banding bundles wherein the bands will be so attached that it will be practically impossible for them to become loosened by the ends thereof slipping sidewise on each other.

Another object is to provide a machine which will prepare the bands so that they may be readily applied to the bundles.

Another object is to provide a method of applying bands to bundles wherein the bands will possess strength, but will at the same time, be capable of ready removal from the bundles.

Further objects and advantages will hereinafter appear.

The invention contemplates the employment of a band of thin flat stock, the ends of which are held together by being looped and clinched into a buckle.

Preferably one end of the band is fastened into the buckle before the band and buckle are placed upon the bundle. The free end of the band may be doubled upon itself at the same time that the other end and buckle are joined.

In order to facilitate the fastening of the buckle to one end of the band and the doubling of the other end thereof upon itself, a machine is provided for performing these operations automatically.

This machine may comprise in general, means for advancing the bands to position for being fastened to the buckle, means for automatically or otherwise supplying the buckles, and means for clinching the ends of the bands.

An embodiment of the invention is herein-after described, while the machine forming

a part thereof is illustrated in the accompanying drawings; wherein,

Fig. 1 is a top plan view of the machine for applying the bands to the buckles;

Fig. 2 is a side elevational view of the machine shown in Fig. 1;

Fig. 3 is an end elevational view of the machine shown in Fig. 1 looking from the left-hand end thereof;

Fig. 4 is a longitudinal vertical sectional view taken on line 4-4 of Fig. 1, showing one of the bulldozing hooks and bending rollers in elevation;

Fig. 5 is a longitudinal vertical section taken on line 5-5 of Fig. 1;

Fig. 6 is a transverse vertical section taken on line 6-6 of Fig. 1, showing the bending rollers in elevation;

Fig. 7 is a fragmentary top plan view of the machine, the yoke covering the anvil arms and links being removed;

Fig. 8 is a transverse vertical section taken on line 8-8 of Figure 1;

Fig. 9 is a plan view of the buckle; and

Fig. 10 a perspective view of a portion of a bundle of cotton ties showing the band and buckle in place thereon.

The machine comprises a bed plate 1 adapted to be suitably secured to a frame or table, not shown. This bed plate is provided with a central opening 2, and a narrower opening 3 extending centrally of the plate from one edge thereof to the first named opening.

Secured to the upper surface of the bed plate and adjacent to the longitudinal sides of the opening 2, are guide members 4 and 5. These guide members are substantially L shape and each have a slot 6 arranged near the top of the vertically extending arm thereof.

A substantially U shaped ram member 7 is provided with lugs extending from each longitudinal side thereof adapted to have a sliding fit within the grooves 6 of the guides 4 and 5. The member 7 is provided centrally of the transverse base thereof with a forwardly projecting head 8. Bulldozing hooks 9 and 10 are pivoted by means of pivot pins 11 and 12 to the outside of the ram upon each side.

Projecting downwardly from the opposite sides of the opening 2 of the bed plate 1, are plates 13 and 14 having cam slots 15

and 16 arranged therein. The hooks 9 and 10 are provided with roller members 17 arranged to have movement within slots 15 and 16. It will thus be apparent that as the ram member 7 is advanced or retracted through the guides 6, the studs 17 will travel in the cam slots 15 and 16, causing the hooks 8 and 10 to rise or fall.

Positioned upon the bed plate 1 adjacent to the left-hand end of the guides 4 and 5, are bending rollers 18 and 19, these rollers being mounted so as to rotate upon vertical axes. Rotatably mounted in suitable bearings 20 and 21, secured to the upper part of the bed plate on the right-hand side thereof, is a crank shaft 22. A detailed description of these bearings is not given since they may be formed in any desirable manner. A connecting rod 23 is attached in any preferred way to the crank shaft 22 at the central offset part thereof, this connecting rod 23 being operatively connected to the ram 7 by means of a wrist pin 24, as is clearly shown in Figure 1 of the drawing.

From the description so far given, it will readily appear that as the crank shaft 22 is rotated, the ram 7 will have a reciprocatory movement within the grooves 6 of the guides 4 and 5 because of the movement of the connecting rod 23. At the same time, as previously described, the hooks 9 and 10 will have an upward and downward movement because of the cam slots 15 and 16.

Slidably mounted upon pins 25 and 26, projecting from the left-hand edge of the bed plate 1 is a substantially L shaped pusher plate 27. Linked members 28 and 29 are operatively connected to each other and to the pusher plate 27 by means of a pin 30. Pivotedly arranged upon elevated bosses 31 and 32 are bell crank anvil arms 33 and 34. The links 28 and 29 are pivotally connected to one end of the bell crank arms 33 and 34 respectively. As the pusher plate 27 is moved backwardly and forwardly, the bell crank arms 33 and 34 will, because of their connection with the links 28 and 29, swing upwardly or downwardly upon their pivotal connection to the bosses 31 and 32.

A coil spring 35 connected to the lower end of the downwardly projecting arm of the member 27 and to a downwardly projecting lug 36 of the bed plate 1 tends at all times to maintain the said plate 27 at the limit of its movement toward the right, thereby keeping the arms 33 and 34 in their raised position.

A yoke cover member 37 is arranged above the links and the arms.

The machine may be operated manually or it may be power driven if it is so desired.

A clutch construction has been illustrated which may be used when the machine is power driven.

This clutch comprises a clutch member 38 having a reduced annular portion 39 and an enlarged portion 40. The clutch is splined upon the crank shaft, being adapted to have a suitable movement thereon.

A bowed leaf spring 41, secured to an upstanding part 42 of the plate 1, has one end bearing against the portion 40 of the clutch. The clutch is thereby held in engaged position.

In order to disengage the clutch a spring pressed pin 43 sliding in the part 42 and another upstanding part 44 is provided. This pin has its engaging end provided with a cam surface so that the clutch will be moved out of engagement when the pin is advanced.

A link member 45 is connected to the opposite end of the pin and to a bell crank lever 46 pivotally arranged to the side of the plate 1.

It will be clear that whenever the lever 46 is depressed the pin will be disengaged from the portion 40 and the spring 41 will throw the clutch into engaged position. As soon as the lever 46 is released the pin will be advanced by its spring and the clutch disengaged.

For a purpose to be hereinafter described, two members 47 and 48 are arranged for transverse adjustment upon the bed plate adjacent the left hand edge of the opening 2. These members have inclined portions 49 and 50 on the side toward the ram.

The buckles which are to be used in the machine may be fed into the operative position from any suitable form of magazine 51. While this magazine may be of the manually operative type, it is preferable that it comprise an automatic type suitably connected and synchronized to, and with, the various working parts of the machine.

In order that the completed band and buckle may be readily extracted from the machine a slot 52 is provided in the bed plate, through which the band and buckle may fall.

The method together with the operation of the machine will now be described:

A band of thin flat stock such as a piece of cotton tie stock is placed in the machine when the parts are in the position shown in Fig. 1. This band is so placed in the machine as to lie between the hooks 9 and 10 and the head 8 of the ram 7. Of course, it is understood that the band will be of such length as is suitable to properly fit and operate within the machine. The band being so placed, the lever 46 is pressed downwardly so that the clutch 38 will operatively connect the crank shaft 22 with a suitable source of power either mechanical or manual.

The ram, as shown in Fig. 1, will be on its rearward stroke; in other words, after the band has been placed in the machine,

and the clutch engaged with the source of power, the ram will slide backwardly, carrying the band therewith at the same time. The opposite end of the band will engage the 5 rollers 18 and 19 during this backward movement of the ram, and will thus be bent backwardly by the rollers so as to lie at right angles to the main portion of the band, thus forming a substantially U-shaped 10 staple.

It will be apparent that the band will bend at a predetermined point thereof, since it is held at each end by the hooks bearing upon one side thereof while the rollers will 15 exert a pressure upon the opposite side thereof. After the ram has reached the limit of its rearward movement, it will start on its forward movement at the same time carrying the band now bent into a substantially 20 U-shaped member along with it. As the ram advances, the hooks 9 and 10 will gradually be depressed by means of rollers 17, travelling in the cam slots 15 and 16, until the said hooks have reached a position 25 in which they will be completely removed from the band. As this operation is occurring a buckle such as is shown in Fig. 9 will be automatically or otherwise fed out of the magazine 51 into the path of the band. The 30 bent ends of the band will engage against the inclined surfaces 49 and 50 and will gradually be bent inwardly. The end of the band engaged against the inclined end of surface 50 will pass through the opening 35 in the buckle as the band is moved forwardly. It will also be seen that the elevated head 9 of the ram 7 will engage the pusher plate 27, forcing the same to the left against the tension of the spring 35. This 40 movement of the plate will carry the links 28 and 29 with it so as to rotate the extremities of the bell-crank arms 33 and 34 downwardly. These arms will engage against the 45 bent ends of the band and will complete the bending thereof and also clinch the end, which is passed through the buckle, about the same, while the free end will be clinched upon the band itself.

The machine is so timed that it will commence its retrograde movement upon the completion of the last named operation. Whereupon, the complete band and buckle will drop through a slot 52 formed in the bed plate. As the parts return to the position shown in Figure 1 the clutch 38 is disengaged until another band may be placed in the machine.

The band and buckle may then be taken and placed around the bundle of cotton ties, or other material, so that the free end of the band can pass upwardly through the central opening in the buckle and then be clinched therearound as shown in Fig. 10.

It will be seen that the free end of the 65 band is doubled where it is hooked and

clinched into the buckle, thereby materially increasing the strength of the joint.

Having described a specific embodiment of the invention, the following claims are appended, it being understood, of course, 70 that the invention is susceptible of many variations and adaptations within the scope of the same.

What I claim is:

1. A machine for preparing the bands for 75 use and for connecting the same to a buckle, comprising a bed plate, a ram slidably arranged thereon, means mounted on and movable with said ram for carrying a tie band; means arranged upon said bed plate for bending the opposite ends of said tie band whereby the tie band is formed into a substantially 80 U-shaped staple.

2. A machine for preparing tie bands for 85 use and connecting the same to a buckle, comprising a bed plate having a central opening therein, a ram arranged upon said bed plate and adapted to have sliding movement within said opening, means carried by said ram for holding a tie band, and means mounted upon said bed plate for engaging the opposite ends of said tie band for bending the same whereby the tie band is formed 90 into a substantially U-shaped staple.

3. A machine for preparing tie bands for 95 use and for connecting the same to a buckle, comprising a bed-plate having a central opening therein, a ram arranged upon said bed-plate and adapted to have sliding movement within said opening, means carried by 100 said ram for holding a tie-band, and means arranged on said bed-plate upon opposite sides of the opening therein for engaging the opposite ends of said tie-band and for bending the same whereby a substantially 105 U-shaped staple is formed.

4. A machine for preparing tie bands for 110 use and for connecting the same to a buckle, comprising a bed-plate having a central opening therein, a ram arranged upon said bed-plate adapted to have sliding movement within said opening, means pivoted to said ram and carried thereby for holding a tie band, means arranged upon said bed-plate for engaging the opposite ends of said tie band whereby the said ends are bent forward and the band is formed into a substantially 115 U-shaped staple.

5. A machine for preparing tie bands for 120 use and for connecting the same to a buckle, comprising a bed-plate having a central opening therein, a ram arranged upon said bed-plate and adapted to have sliding movement within said opening, means pivoted 125 to said ram and carried thereby for holding a tie band, means arranged upon said bed-plate upon opposite sides of said opening for engaging the opposite ends of said tie band and for bending the same so as to form a substantially 130 U-shaped staple.

6. A machine for preparing tie bands for use and for connecting the same to a buckle, comprising a bed-plate having a central opening therein, guide members arranged upon said bed-plate upon opposite sides of said opening, a ram having a sliding engagement with said guide members, means carried by said ram for holding a tie-band, and means mounted upon said bed-plate adjacent to said guide members for engaging opposite ends of said tie-band and bending the same forwardly whereby the guide band is formed into a substantially U-shaped staple.
- 15 7. A machine for preparing tie bands for use and for connecting the same to a buckle, comprising a bed-plate having a central opening therein, guide members arranged upon opposite sides of said opening, a ram having projecting flanges slidably engaged in said guide members, means carried by said ram for holding a tie band, rollers arranged upon said bed-plate adjacent to said guide members for engaging the opposite ends of said tie band, whereby the same are bent forwardly at a point between said rollers and said means carried by said ram.
- 20 8. A machine for preparing tie bands for use and for connecting the same to a buckle, comprising a bed-plate having a central opening therein, guide members provided with longitudinally extending grooves arranged upon opposite longitudinal sides of said opening, a ram having longitudinally extending flanges upon opposite sides thereof adapted to engage in said grooves, means pivoted to said ram and carried thereby for holding a tie band, and rollers arranged upon said bed plate on opposite sides of said opening adjacent to said guide members for engaging the opposite ends of said tie band whereby the latter are bent forwardly at a point between the rollers and the means pivoted to said ram.
- 25 9. A machine for preparing tie bands for use and connecting the same to a buckle comprising, a bed-plate having a central opening therein, guide members arranged upon opposite sides of said opening, a ram arranged upon said bed-plate and adapted to have sliding movement within said guides, means pivoted to said ram and carried thereby, said means being adapted to have a raising or lowering movement during the sliding movement of said ram, and rollers arranged upon said bed-plate adjacent to said guide members.
- 30 10. A machine for preparing tie bands for use and connecting the same to a buckle, comprising a bed plate, a ram member slidably arranged thereon, means for actuating said ram member, hook members carried by said ram member and pivoted thereto adapted to have a rising or falling movement during movement of said ram member, and

means arranged on said bed plate upon the opposite sides of said ram member, said ram member and said means carried thereby being adapted to hold a tie band so that the opposite ends thereof will be engaged by said last-named means during the sliding movement of said ram thus bending the opposite ends of said tie band forwardly and forming the same into a substantially U-shaped staple.

75 11. A machine for preparing tie bands for use and for connecting the same to a buckle, comprising a central bed-plate, a ram arranged thereupon and adapted to have slideable movement within said opening, means for actuating said ram, hooks pivoted to said ram so as to travel therewith, and means carried by said bed-plate for causing said hooks to have a rising and falling movement during the movement of the ram.

80 12. A machine for preparing tie bands for use and for connecting the same to a buckle, comprising a bed plate, means slidably arranged thereon, means carried by said first named means adapted to have oscillatory movement during the movement of the latter, said means being adapted to receive a tie band, means arranged upon said bed plate for bending the opposite ends of said tie band, and means actuated by said first-named means for clinching the bent ends of the tie band downwardly.

85 13. A machine for preparing tie bands for use and connecting the same to a buckle, comprising a bed-plate, a member slidably mounted thereon, means for actuating said member, means carried by said member for holding a tie band, means carried by said bed plate for bending the opposite ends of said tie band, and means actuated by said member for clinching the bent ends of the tie band downwardly.

90 14. A machine for preparing tie bands for use and connecting the same to a buckle, comprising a bed-plate; a ram member slidably arranged thereon, means for actuating said ram, means carried by said ram for holding a tie band, means arranged upon said bed plate for engaging the opposite ends of said tie band and bending the same forwardly, means actuated by said ram for clinching the bent ends of said tie bands downwardly.

95 15. A machine for preparing tie bands for use and for connecting the same to a buckle, comprising a bed plate, a ram member slidably arranged thereon, means carried by said bed plate for bending the opposite ends of said tie band forwardly, means carried by said bed plate for bending the forwardly bent ends of the tie band downwardly upon the band and means actuated by said ram for clinching the bent ends upon the band.

100 16. A machine for preparing tie bands for use and for connecting the same to a buckle,

comprising a bed plate, a ram member slidably arranged thereon, means carried by said bed plate for bending the opposite ends of said tie band forwardly, one of said bent 5 ends being adapted to be passed through a buckle, means carried by said plate for bending the forwardly bent ends of the tie band downwardly upon the band, and means actuated by said ram for clinching the bent 10 ends upon the band and about the buckle.

17. A machine for preparing tie bands for use and for connecting the same to a buckle,

comprising a bed plate, a ram member slidably arranged thereon, means carried by said bed plate for bending the opposite ends of 15 said tie band forwardly, means carried by said bed plate for bending the forwardly bent ends of the tie band downwardly upon the band, and slidable means actuated by said ram and operatively connected to a 20 plurality of pivoted members for clinching the bent ends upon the band.

In testimony whereof I affix my signature.
MORTIMER P. LAWTON.
